POST INSULATOR

Alpha D. Lantz, 91 37th St. SW., Barberton, Ohio

Filed Aug. 9, 1962, Ser. No. 71,224

Term of patent 14 years

(Cl. D26—10)

FIG. 1 is a front elevation view of a post insulator, showing my new design;

FIG. 2 is a top plan view thereof; and

FIG. 3 is an end view thereof taken from the left end in FIG. 1.

I claim:
The ornamental design for a post insulator, as shown.
